UNITED STATES PATENT OFFICE

JOHN RAWLES, OF MACOMB, ASSIGNOR OF ONE-HALF TO D. F. CHIDESTER
AND G. H. McELVAIN, BOTH OF BUSHNELL, ILLINOIS.

CAR-COUPING.

SPECIFICATION forming part of Letters Patent No. 362,996, dated May 17, 1887.

Application filed February 3, 1887. Serial No. 226,386. (No model.)

To all whom it may concern:

Be it known that I, JOHN RAWLES, a resident of Macomb, in the county of McDonough and State of Illinois, have invented a new and 5 useful Improvement in Car-Couplings, of which the following specification will enable others skilled in the art to make and use the same, reference being had to the accompanying drawings, and to the letters of reference marked 10 thereon.

This invention has for its object the construction of a safety car-coupling especially adapted to freight-cars, and that is simple in construction, durable and very efficient in operation, 15 which does not endanger the life of the operator, and its novelty will be fully set forth in the following specification and pointed out in the claims.

In the drawings, Figure 1 is a perspective 20 view of the coupling attached to the car-body. Fig. 2 is a top view of the draw-head detached. Fig. 3 is a longitudinal elevation of Fig. 2, taken in center, showing the inner construction of the draw-head and coupling-pins.

25 Similar letters indicate like parts in each figure, in which—

A represents the car-body. B represents the draw-head, constructed with upper and lower jaws, the upper jaw forming guides and a rest 30 for the coupling-pins *i i i*. The lower jaw is constructed with sufficient strength to receive the shock produced when the cars come together when in the act of coupling.

On each side of the draw-head B are formed 35 ears *s s*, in which are fitted the rear ends of the coupling-clevis C. The bolt *t* passes through the ears and through the ends of the coupling-clevis and draw-head. (See Fig. 2.) The draw-head is constructed with three pin-holes for 40 coupling-pins. In the rear of the center hole is a hole for the gravity-pin J. (See Figs. 2 and 3.)

The coupling-pins *i i i* are connected together at the top by means of the bolt K. They 45 fit loosely on said bolt, so that each pin sustains an equal amount of the draft. In the rear of the center pin and connected therewith is a loosely-pivoted gravity-pin, J. (See Fig. 3.) This gravity-pin is about one-third longer than 50 the coupling-pins *i i i*. This gravity-pin is arranged so that the lower end extends back out

of plumb when down, as shown in Fig. 3, and its purpose is, when the pins *i i i* are raised up, as shown in dotted lines in Fig. 3, to (by its own gravity) pass into and rest in the concave seat P, (see Fig. 3,) and hold the pins *i i i* up out of the way when the link or coupling-clevis C is entering between the jaws of the draw-head, and when the link or coupling-clevis presses back against the gravity-pin it 60 forces it out of the concave seat P. Then, by their own weight, the pins *i i i* and gravity-pin J drop down to their shown position in Fig. 3.

The coupling-pins *i i i* and gravity-pin J are all operated by means of the shaft *w*, which is 65 attached by suitable bearing to the car-body, and to which are firmly attached the arms *a a*, which, by means of short chains, are attached to each end of the bolt K. (See Fig. 1.) Each end of the shaft *w* is bent at right angles to 70 form handles *n n*. Attached to the left arm *a* is an upright rod, *b*, which extends to the top of the car-body with suitable hand-hold, so that the operator can operate the coupling-pins without danger to life from the top of 75 the car.

The shaft *l* extends across the car-body, and is constructed and attached thereto the same as the shaft *w*, and has firmly attached to it the arms *b*, which extend outward and two or 80 three inches beyond the pivot-bolt *t*, one on each side of the draw-head, (the right arm not shown.) These arms, by means of short chains, are connected to the pins *g g* on the coupling-clevis C. On the left arm is attached an up- 85 right rod, *b*, which extends to the top of the car with suitable hand-hold. This shaft *l*, with its appliances, is for the purpose of operating the coupling-clevis C by raising it up to its shown position in Fig. 3, which can be done 90 either from the top of the car or at either side without danger to life.

Operation: The operation of this car-coupling is in the very extreme of simplicity. The operator can either from the top of the car or 95 the sides operate the coupling without being exposed to danger. If the operator is on top of the car and wishes to couple, he first sets the coupling-pins *i i i* by grasping the upright rod *b*, that is attached to the arm *a* on the shaft *w*, and draws up the pins *i i i* until the gravity-pin J passes into the concave seat P, which 100

movement will hold up the coupling-pins *i i i*, as shown in dotted lines in Fig. 3. Then, by means of the rod *b*, attached to the arm *h* on the shaft *l*, he can raise up the coupling-clevis *C* to its shown position in Fig. 3. The outer end of the arm *h* extends out beyond the pivot-bolt *t*, and by means of short chains draws the coupling-clevis *C* forward sufficient to pass the center of the pivot-bolt *t*. The clevis *C* is then raised up easily, and when the cars come together the coupling-clevis *C* strikes the gravity-pin *J* and presses it back out of the concave seat *P*, which causes all the pins to drop together and couple the cars, and to uncouple the pins *i i i* are raised up as before, and when the cars are apart the coupling-clevis *C* assumes the position shown in Fig. 1. When coupling or uncoupling at either side of the car, the handles *n n* on the shaft *w* and the handles *e e* on the shaft *l* are used to operate the coupling devices the same as above described. This coupling can be coupled to any of the old-style draw-heads by using a common link.

Having thus described my invention, what I

claim as new, and desire to secure by Letters Patent, is—

1. In a car-coupling, the draw-head *B*, having an upper and lower jaw, and provided with ears *s s*, in combination with the coupling-clevis *C*, having pins *g g*, and secured to the draw-head *B* by means of the bolt *t*, and shaft *l*, having suitable handles at each end, and arms *h* and upright rod *b*, attached substantially as shown and described, for the purpose specified.

2. In a car-coupling, the draw-head *B*, constructed with an upper and lower jaw and concave seat *P*, in combination with a series of coupling-pins, *i i i*, loosely attached together by means of the bolt *K*, the gravity-pin *J*, pivoted to and in the rear of the center coupling-pin *i*, the projecting arms *a a*, rock-shaft *w*, and upright rod *b*, substantially as shown, and for the purpose specified.

JOHN RAWLES.
